UNITED STATES PATENT OFFICE.

JAMES B. BAIRD, OF AVONMORE, PENNSYLVANIA; C. D. ROBERTSON, WILLIAM GOUDY, AND MARY E. BAIRD, EXECUTORS OF SAID JAMES B. BAIRD, DECEASED, ASSIGNS TO THE NATIONAL ROLL AND FOUNDRY COMPANY, OF AVONMORE, PENNSYLVANIA, A CORPORATION OF OHIO.

SCOURER FOR ROLLING-MILLS.

1,279,219.

Specification of Letters Patent. Patented Sept. 17, 1918.

Application filed March 15, 1915. Serial No. 14,355.

To all whom it may concern:

Be it known that I, JAMES B. BAIRD, a citizen of the United States, residing at Avonmore, in the county of Westmoreland and State of Pennsylvania, have invented a new and useful Scourer for Rolling-Mills, of which the following is a specification.

At the present time sheet iron is produced by passing heated bars between heavy rolls 10 until the metal has been reduced to desired gage. These rolls are machined and polished and their working faces are initially substantially concentric with their axes and the upper roll is generally so mounted as to be capable of some vertical movement at each passage of material. The working faces of the rolls determine the character of the product and it has, therefore, long been recognized that these working surfaces should be maintained in a well polished condition in order to produce the highest character of product.

During the operation the metal becomes oxidized in spots and there are thus produced flakes of metallic oxid of various sizes. 25 Owing to the great pressure exerted by the rolls upon the hot metal, some of these oxid flakes stick to the working faces of the rolls and, during the rotation of the rolls, come again between the rolls and the metal. Some 30 of these particles remain stuck to the rolls for a considerable number of rotations and finally the working faces of the rolls become pitted by this action to a considerable extent, the quality of the product gradually deteriorating until the operatives are forced to suspend operation to permit the scouring or repolishing of the rolls.

Heretofore this scouring or repolishing has been accomplished by placing a scouring 40 block of abrasive material, such for instance as carborundum, upon one end of a board and, by using this board as a lever placed over the stationary bar forming a part of the frame of the rolls, and by applying the 45 weight of one or two operatives to the outer end of the board, forcing the scouring block against the surface of the roll. During this operation the board is swung and shifted laterally on its fulcrum. This operation 50 serves to remove the adhering particles from the rolls but, because the operation interferes with the productive operation of rolls and because the operatives are generally

working upon a tonnage basis, the cleansing operation is delayed generally to such an extent that the rolls are badly pitted and consequently there must need be not only the scouring operation, but also an actual resurfacing of the rolls. Owing to the crudity of the apparatus and the amount of weight applied, the scouring operation results in the formation of spiral striæ in the surface of the rolls and the operation requires the expenditure of from one to two and one-half hours of each shift of eight hours. After the rolls have been cleansed in this manner, the spiral striæ, although not deep, nevertheless serve to slightly tear the surface of the metal passed between the rolls so that exaggerated diagonal striæ are produced in the surfaces of the product of the machine. During the operation of the rolls, they become heated and they inevitably become distorted to some extent from true cylindricity which, however, does not interfere with the proper co-operation of the rolls owing to the possibility of vertical adaptability of the upper rolls.

The object of my present invention is to produce an apparatus which may be applied to the rolls of a rolling mill in such manner as to be effective in maintaining the rolls in their initial polished condition without interfering to any extent with the concurrent use of the rolls in the production of sheet metal, the apparatus being of such character that no appreciably-spiral striæ will be formed upon the surface of the roll.

The accompanying drawings illustrate my invention. Figure 1 is a side elevation of a pair of rolls equipped with my attachments; Fig. 2 a fragmentary front elevation; Fig. 3 an end elevation on a larger scale of the scouring member carrier of the attachment; Fig. 4 a front elevation thereof; and Fig. 5 a perspective detail of the nut pin for the carrier.

In the drawings, 10 indicates the main housing or frame of a rolling mill of ordinary type, 11 the upper roll and 12 the lower roll. Applied to each of the rolls is one of my attachments. Each of these attachments comprises a main shaft 13 which is provided through the greater portion of its length with an endless screw 13' comprising righthand and lefthand portions connected at their ends in a common manner. The shaft

13 at one end is provided with a journal 14 journaled in a cup 15 carried by a spring pressed plunger 16 which is mounted in the frame 10 parallel with the axis of one of 5 the rolls. At the other end the shaft 13 is provided with a diametrical slot 17 to receive a coupling member 18 which is also formed to receive the square end of a shaft 19 journaled in a bracket 20 attached to the 10 frame 10, the arrangement being such that the plunger 16 serves to normally maintain the shaft 13 in driving connection with its shaft 19. Each shaft 19 is provided with a beveled gear 21 which meshes with a bevel 15 gear 22, the two beveled gears 22 being carried by a vertical shaft 23 journaled in the two brackets 20 and driven by any suitable means such, for instance, as a small electric motor 24 mounted upon a bracket 25 which 20 may be conveniently attached to the frame 10. Journaled on the shaft 13 is a frame 26 having pockets 27 at its outer end for the reception of bearing blocks 28 which are detachably held in place by clamping plates 25 29 and bolts 30. The blocks 28 form bearings for the shaft of a rotary scouring member 31. I have found in practice that a satisfactory scouring member is a medium grade of carborundum. One end of the shaft of 30 the scouring member 31 carries a gear wheel 32 which, when the parts are in place, meshes with an intermediate gear 33 which is in turn meshes with a gear 34 which is splined upon the shaft 13, the gear 34 having a rotatable, axially interlocking connection 35 with the frame 26. That portion of the frame 26 which is journaled upon shaft 13 carries a pivoted nut pin 37 of common 40 form to lie within the endless screw threads 13' in a well known manner, the arrangement being such that rotation of the shaft 13 will serve to reciprocate the frame 26 lengthwise of the shaft and at the same time will serve to rotate the scouring member 31. 45 Journaled in the frame 10 parallel with each shaft 13 is a track bar 38 which carries a track 39 corresponding to the axial conformation of the adjacent rolls 11 or 12. The track bar 38 is connected to a lever 40' which in turn is connected to a segment lever 40 through the medium of a spring connection 41 and the segment lever 40 may be held in any desired position of adjustment by means of a segment 42. 50 Frame 26 carries a roller 43 which rests upon the track 39, the arrangement being such that the frame 26 is biased by its weight so as to maintain the roller 43 in contact with track 39 and so that a shifting of the track 39 will shift the scouring member toward or from the adjacent roll and, when the scouring member is shifted into engagement with the roll, it will be yieldingly maintained in that engagement by the spring 60 connection 41.

Owing to the character of the material which adheres to the rolls, the scouring member is apt to lose its efficiency because the particles stick to the scouring member and in order to obviate this difficulty, I 70 pivot upon frame 26 a supplemental frame 45 which at one end carries a common form of cleaning roll 47 which is a knurled or spirally toothed metal roller and this roller may be thrown into engagement with the 75 circumference of the scouring member by means of the adjusting screws 49, the contact between the scouring member and the cleaning roll being very light and just sufficient to keep the scouring roll in proper condition. 80 At times the cleaning member may be withdrawn, if desired.

In mounting the scouring members relative to the rolls I have found it desirable to arrange them so that the direction of rotation of the scouring member will be opposite to that of the adjacent roll so that the direction of movement of the contacting portions of the peripheries of the roll and scouring member will be the same and so that the circumferential speed of the scouring member will be a little less than the circumferential speed of the roll, thus producing a slight rearward or dragging component which I have found to be exceedingly effective in 95 loosening and removing the particles adhering to the surface of the roll.

The spring connection 41 is comparatively light so that the scouring member is held against the roll with only enough pressure 100 to insure a light contact following the variations of the roll from true concentricity, the intention being not to materially grind the surface of the roll but to merely maintain a sufficient contact of the scouring member 105 upon the roll to insure the removal of adhering particles.

In practice I have found that a scouring member several inches in length is desirable because, by making the pitch of the threads 110 13' comparatively slow, the movement of the scouring member longitudinally of the rolls is comparatively so slight that any striæ which may be found upon the surface of the roll are so nearly circumferential (the 115 circumferential speed of the roll being comparatively high) that there will be no appreciable tearing action of such striæ upon the sheet material as it passes between the rolls.

The attachments which have been described are arranged adjacent each roll and preferably upon the furnace side of the stand, so that they may be under the convenient control of the head operative. They 125 are of such character that they are not in the way either of the operative or the material, so that the use of the rolls in the production of sheet metal may be the usual use without interference and, as the entire sur- 130

face of each roll is traversed by the scouring member at frequent intervals, the said surfaces are at all times maintained in the most effective condition for the production of 5 sheets of the highest quality without the necessity of interrupting the operation of the rolls and consequently cutting down the tonnage of the output. The longitudinal movement of the scouring member upon the rolls 10 maintains the scouring member in proper condition and prevents the formation of circumferential grooves therein.

I claim as my invention:

1. The combination with a rolling mill, of 15 a rotary scouring member arranged adjacent the working face of a roll of said mill, means for holding said scouring member in contact with the said working face, means for automatically reciprocating said scouring member longitudinally of the roll, and means for rotating said scouring member in a direction opposite to the direction of rotation of the contacted roll but at a slightly slower surface speed.
2. The combination with a rolling mill, of 25 a shaft journaled substantially parallel with one of the rolls and provided with an endless thread comprising righthand and lefthand portions, a scourer frame journaled upon 30 said shaft and provided with a nut pin traversing said thread, a rotary scourer member journaled in said frame, and rotative driving connections between said scourer member and shaft.
3. The combination with a rolling mill, of 35 a double threaded shaft journaled adjacent a roll, a carrier mounted upon said shaft, means carried by said carrier for engaging the thread of the shaft to cause reciprocation 40 of the carrier upon the shaft, a gear splined upon the shaft and axially movable thereon with the carrier, a rotary scouring member journaled in the carrier, connections between 45 said rotary scouring member and the gear whereby rotation of the threaded shaft will rotate the scouring member, a track arranged adjacent a roll and supporting the carrier, and a yielding support for said track.
4. The combination with a rolling mill, of 50 a double threaded shaft journaled adjacent a roll, a carrier mounted upon said shaft, means carried by said carrier for engaging the thread of the shaft to cause reciprocation 55 of the carrier upon the shaft, a gear

splined upon the shaft and axially movable thereon with the carrier, a rotary scouring member journaled in the carrier, connections between said rotary scouring member and the gear whereby rotation of the threaded 60 shaft will rotate the scouring member, a rotary cleansing member arranged adjacent the scouring member, a carrier for said cleansing member, and means for swinging said carrier to swing the cleansing member 65 into and out of contact with the scouring member.

5. The combination with a rolling mill, of a double-threaded shaft journaled adjacent a roller, a carrier mounted upon said shaft, 70 means carried by said carrier for engaging the thread of the shaft to cause reciprocation of the carrier upon the shaft, a gear splined upon the shaft and axially movable thereon with the carrier, a rotary scouring member 75 journaled in the carrier, connections between said rotary scouring member and the gear whereby rotation of the threaded shaft will rotate the scouring member, and means for holding the scouring member in contact with 80 a roll.

6. A scouring device for rolls comprising a rotary threaded shaft, a carrier mounted upon said shaft, a connection between said carrier and the threads of the shaft to cause 85 axial movement of the carrier by rotation of the shaft, a scouring member rotatably mounted in the carrier, and driving connections between the shaft and scourer producing rotation of the scourer by rotation of the 90 shaft.

7. A scouring device for rolls comprising a rotary threaded shaft, a carrier mounted upon said shaft, a connection between said carrier and the threads of the shaft to cause 95 axial movement of the carrier by rotation of the shaft, a scouring member rotatably mounted in the carrier, a gear splined upon the shaft and connected to the carrier to partake of its axial movement, and driving connections between said gear and the scouring member.

In witness whereof, I, JAMES B. BAIRD, have hereunto set my hand at Avonmore, Pennsylvania, this 27th day of February, A. 105 D. one thousand nine hundred and fifteen.

JAMES B. BAIRD.
